DESIGN FOR A COMBINED THERAPEUTIC LAMP AND SUPPORT

Frank Furedy, Chicago, Ill., assignor to Sun-Kraft, Inc., Chicago, Ill., a corporation of Illinois

Application May 13, 1940, Serial No. 92,334

Term of patent 14 years

To all whom it may concern:

Be it known that I, Frank Furedy, a citizen of the United States, residing at Chicago, Cook County, Illinois, have invented a new, original, and ornamental Design for a Combined Therapeutic Lamp and Support, of which the following is a specification, reference being had to the accompanying drawing forming a part thereof and wherein:

Figure 1 is a face view in perspective of a therapeutic lamp and support embodying the present design; and

I claim:

The ornamental design for a combined therapeutic lamp and support, substantially as shown.

FRANK FUREDY.
